UNITED STATES PATENT OFFICE.

WILLIAM C. BRINTON, JR., OF MANOA, PENNSYLVANIA, ASSIGNOR, BY DIRECT AND MESNE ASSIGNMENTS, TO PHILIPS-BRINTON COMPANY, OF KENNETT SQUARE, PENNSYLVANIA, A CORPORATION OF PENNSYLVANIA.

ELECTRIC CONNECTION.

1,177,920.

Specification of Letters Patent.

Patented Apr. 4, 1916.

Application filed November 7, 1914. Serial No. 870,733.

To all whom it may concern:

Be it known that I, WILLIAM C. BRINTON, Jr., a citizen of the United States, residing at Manoa, county of Delaware, and State of Pennsylvania, have invented a new and useful Improvement in Electric Connections, of which the following is a full, clear, and exact description, reference being had to the accompanying drawings, which form 10 a part of this specification.

My invention relates to that form of electrical connection whereby an insulated electric wire or cable is detachably connected to a binding post or other terminal for the 15 passage of an electric current therethrough, the joint being entirely enveloped and protected by insulating material.

In my improved connection a screw cap 20 of insulating material is slipped on to the end of the cable, the wire extending from the end of the cable is connected to the binding post in a manner to be hereinafter described, and the cap is screwed into place on the binding post support, the arrangement 25 being such that the electric terminals will be clamped together in such relation as to insure the best possible electric conduit, and at the same time lock the end of the cable securely in the joint. This is accomplished without the small screws usually 30 used in the connection of wires to terminals, thus avoiding the inconvenience accompanying the use of such screws, making a more positive connection, and effecting a saving 35 of time in making or breaking connections.

In the preferred form of the invention, the construction and arrangement are such that the cable may turn freely relatively to the fixed binding post support without affecting 40 the electric connection; it being, therefore, a matter of indifference whether, in screwing or unscrewing the screw cap, the cable turns with it.

Another advantage of the invention is 45 that it is impossible, by pulling upon the cable, to disrupt or affect the electric connection.

Having now set forth in a general way the primary objects and advantages of my 50 invention, I will describe same in detail in connection with the accompanying drawings, in which—

Figures 1 and 2 are sectional views showing steps in the process of forming a con-

nection with my improved device. Fig. 3 55 is a similar view of the finished joint. Fig. 4 is a developed view of an intermediate link of the joint. Fig. 5 is a perspective view of said link. Fig. 6 is a sectional view showing a modification in structure. Figs. 60 7 and 8 are sectional views, corresponding to Fig. 2, of a modification, the two views being taken at right angles to each other. Fig. 9 is a plan view of the binding post 65 of Figs. 7 and 8. Fig. 10 is a plan view of a binding post of still another modification. Fig. 11 is a sectional view of the finished joint of Figs. 7 and 8, but somewhat modified in construction.

As shown in Figs. 1, 2 and 3, the stationary terminal member comprises a binding post *a* and support *b*, the former being turned down as it emerges from its support to form a projection *c*. An intermediate link *d* is stamped out of a thin strip of conducting material as shown in Fig. 4. This link is bent around into the ring form shown in Fig. 5, the two end holes *e* overlapping. This link is then slipped over the projecting end *c* of the binding post and 80 held loosely thereon by cotter pin *f*.

The end of the insulated wire *g* is scraped free of insulation as shown at *h*, and the cap *i* of insulating material is strung over the wire *h* onto the insulated portion. The 85 bare wire *h* is then passed through holes *j* in link *d*, as shown in Fig. 1. The bare wire is then pulled farther through the link and wound about itself as shown in Fig. 2. Next the cap *i* is slid down and screwed onto 90 the support *b*, the recess *k* in said cap being of sufficient depth to compress the link *d* down upon the projection *c*, as shown in Fig. 3.

In connections of this form the orifice in 95 the cap is necessarily made a close fit on the insulated wire, in order to provide bearing and support for same. Therefore, in the ordinary construction, when screwing the cap into this form of connection, the wire there- 100 in is apt to be turned with the screwing motion, tending to impair or destroy the electric connection of the wire to binding post. In the embodiment of my invention just described, the link *d* is swiveled upon the binding post and is readily turnable thereon, allowing the turning of the end of the wire 105 with the screwing on of the cap without in-

any way impairing the electrical connection. It can be readily seen from Fig. 3 that the screwing down of the cap presses the upper reach of the link firmly between the bare 5 wire and the projection on the end of the binding post, insuring good electrical connection. The holes j in link d are made elongated sufficiently to insure not abrading the wire passing through them when bent into 10 the shape shown in Fig. 3. Further the narrowing of the link between holes e and j provides for flattening the link without distortion of the central part thereof. If the cap i is not made to fit tightly over the insulated wire as stated, it does not only not 15 form a good support for said wire, but in allowing the cap to be turned in relation thereto in the process of screwing into place, the opening in the cap tends to wear and 20 abrade the insulation on the wire. The orifice in my improved cap holds the wire passing therethrough firmly, and by being slightly rounded at m , allows free bending 25 of the wire without danger of cutting the insulation.

A modified form of structure is shown in Fig. 6. In this case, the connection is made exactly as described above, but the members in threaded engagement are here made of 30 metal instead of the hard rubber or other composition used for a non-conductor. The cap i' has cast therein the threaded metal ring l . Similarly the threaded part n is made of metal, in one piece with the binding 35 post a' . This makes a much cheaper structure, and the engaging threads, being of metal, are more durable and perfect than the composition threads. The embodiment of my invention shown in Sheet 2 of the drawings 40 does not possess all the advantages of the embodiment shown on Sheet 1, in that the intermediate link, while swiveled upon the binding post has no unlimited turning movement thereon; but the structure is 45 available for use where it is desired to establish a plurality of electrical connections with a plurality of binding posts, and is especially applicable to electric light sockets. In this construction, b^2 represents the support 50 for the two fixed binding posts a^2 having the projecting ends c^2 . The two intermediate links d^2 are applied to the ends c^2 of the binding posts a^2 as hereinbefore described. 55 The two ends of insulated wire g^2 have sleeved upon them the cap i^2 , and their bare ends h^2 are respectively secured to the two intermediate links d^2 , as hereinbefore described. A partition o extends upward from 60 the support a^2 and has a relatively narrow projection p having a V-shaped recess in its upper end, thus allowing the wires h to extend on opposite sides of the partition and projection, which maintain the wires insulated 65 from each other. When the cap i^2 is

slid down and screwed onto the support b^2 , the partition o extends up into the recess k^2 within the cap, the projection p extends up into the cable-receiving orifice in the cap, and the links d^2 are compressed down upon the projections c^2 , as shown in Fig. 11, the two bare ends of wire h^2 extending respectively on opposite sides of the partition o and projection p . In the last named figure, however, the construction differs somewhat 70 from that shown in Figs. 7 and 8, in that the base b^3 has a screw threaded orifice to receive the special fitting r carrying the two binding posts a^3 . 75

In Fig. 10 I have indicated how the invention may be adapted to three or more electrical connections by forming on the support three or more partitions s adapted to separate from each other the separate wires. 80

The various modifications shown are 85 merely illustrative of the possibility of varying the mechanical details without departing from the essential invention.

Having now fully described my invention, what I claim and desire to protect by Letters Patent is:

1. An electric connection comprising a terminal member, a cap adapted to be connected with the terminal member, a wire carried by the cap, and an intermediate link swiveled upon the terminal member and to which the wire is adapted to be attached, said link being compressible between the terminal member and cap in the connection of the cap with the terminal member. 100

2. An electric connection comprising a terminal member, a hollow cap adapted to be threaded thereon, a wire extending through the head of the cap, into the hollow interior thereof, and an intermediate compressible member secured to and supported by the terminal member and connected with the end of the wire within the cap and adapted with the wire to be compressed between the head of the cap and the terminal member in the rotation of the cap to secure the same to the terminal member. 105

3. An electric connection comprising a terminal member, a cap adapted to be connected therewith, a wire carried by the cap, and an intermediate link both swiveled and rotatable upon the terminal member and to which the wire is adapted to be attached, said link being compressible between the terminal member and cap in the connection of the cap with the terminal member. 115

4. An electric connection comprising a terminal member including a binding post, a hollow cap adapted to be applied to the terminal member, a wire extending into the inside of the cap, an intermediate link adapted to slip upon the binding post so as to be turnable thereon and to which the wire is adapted to be connected, said link being compressible between the cap and terminal 120

125

member in applying the cap to the terminal member, thereby forcing the wire into close contact with the binding post.

5. An electric connection comprising a terminal member including a binding post, a cap adapted to be connected with the terminal member, a wire carried by the cap, an intermediate ring-shaped link having orifices adapted respectively to slip upon the binding post and to receive the wire, said link being compressible between the cap and terminal member in connecting the same together.

6. An electric connection comprising a terminal member including a binding post and provided with a threaded portion, a hollow cap threaded to engage the terminal member, a wire extending through the cap, an intermediate ring-shaped link having orifices adapted respectively to slip upon the binding post and to receive the wire, said link being compressible between the cap and terminal member in screwing the former upon the latter.

25 7. An electric connection comprising a terminal member including a binding post, a cap adapted to be connected with the terminal member, a wire carried by the cap, an intermediate ring-shaped link having orifices adapted respectively to slip upon the binding post and receive the wire, said link, between two orifices adapted to engage respectively the wire and binding post, having a narrow neck and being compressible

between the cap and terminal member in connecting the same together.

8. An electric connection comprising a terminal member, a cap adapted to be connected therewith, a wire carried by the cap, and an intermediate compressible link swiveled upon the terminal member, said link having a pair of apertures adapted to permit the attachment thereto of the wire.

9. An electric connection comprising a terminal member including a binding post and provided with a threaded portion, a hollow cap threaded to engage the terminal member, a wire extending through the cap, an intermediate link comprising a strip having an orifice at each end, a pair of apertures on opposite sides of its center and a narrow neck between each end orifice and the adjacent aperture, said link being adapted to be bent into a ring with its end orifices overlapping and slipped over said projection, the wire being adapted to be connected with the link by engaging said apertures, said link being compressible between the cap and terminal member in screwing the former upon the latter.

In testimony of which invention, I have hereunto set my hand, at Philadelphia, on this 4th day of November, 1914.
